UNITED STATES PATENT OFFICE.

GEORGE D. HAWORTH, OF CHICAGO, ILLINOIS.

METALLIC FELLY.

SPECIFICATION forming part of Letters Patent No. 319,410, dated June 2, 1885.

Application filed March 9, 1885. (No model.)

To all whom it may concern:

Be it known that I, GEORGE D. HAWORTH, a resident of the city of Chicago, county of Cook, and State of Illinois, have invented certain new and useful Improvements in Metallic Fellies, of which the following is a specification.

The object of my invention is to provide a remedy for rim-bound wheels, and to produce a metallic felly of uniform strength and rigidity throughout.

In the drawings accompanying and forming a part of this specification, Figure 1 represents a longitudinal vertical section of a portion of an iron felly constructed in accordance with my invention. Fig. 2 represents an end of a section of a felly with a dowel-pin attached. Fig. 3 represents an end of a section of a felly provided with a suitable slot to receive the dowel-pin shown in Fig. 2. Fig. 4 is a view of the interior surface of a portion of a felly, illustrating the receptacle for the end of a spoke. Fig. 5 is a plan of the elastic washer, and Fig. 6 is a cross section of the same.

a represents sections of the felly.
b are spoke-bearings.
c are spokes.
d are intervening ledges on the conjoining ends of sections a.
e are elastic washers.
f represents a dowel-pin rigid on cross-bar g.
h is a cross-bar slotted to receive dowel-pin f.
i represents the portion of the dowel-pin that rests against the outer part of cross-bar h.
k is the slot in cross-bar h.

l are enlarged receptacles in spoke-bearings b.

The sides of slot k fit closely over the dowel-pin and effectually prevent lateral displacement. The extreme projection of the dowel-pin rests on the inner surface of a section, and combines with cross-bar h and surface i, to form a truly circular felly of uniform strength and rigidity throughout. The coinciding ledges d may be readily removed to an extent sufficient to remedy rim-binding, either by using a saw while the wheel is integral, or by detaching the sections and cutting away the superfluous portion.

I claim as new and desire to secure by Letters Patent—

1. A means of providing in metallic fellies a remedy for rim-bound wheels, consisting in diminished intervening and coinciding ledges on the conjoining ends of the felly-sections, substantially as described.

2. The means herein set forth for forming an iron felly of uniform strength and rigidity throughout, consisting in the combination, with conjoining ends of different sections of the felly, of a dowel-pin rigid on an end of a section, and having its extreme projection resting on the inner surface of the concavity of the opposite section, and a cross-bar on the end of the opposite section, provided with a slot adapted to receive the dowel-pin and effectually prevent either centripetal or lateral displacement therein.

GEORGE D. HAWORTH.
